UNITED STATES PATENT OFFICE.

GEORGE B. THOMAS, OF HARTFORD, CONNECTICUT, ASSIGNOR TO THE PERKINS ELECTRIC SWITCH MANUFACTURING COMPANY, OF SAME PLACE.

DESIGN FOR A LINING FOR SWITCH-CAPS.

SPECIFICATION forming part of Design No. 33,304, dated October 2, 1900.

Application filed August 27, 1900. Serial No. 28,264. Term of patent 14 years.

To all whom it may concern:

Be it known that I, GEORGE B. THOMAS, a citizen of the United States of America, residing in Hartford, in the county of Hartford,

5 State of Connecticut, have invented and produced a Design for a Lining for Switch-Caps, of which the following is a specification.

My design for switch-cap lining is illustrated in the accompanying drawings, in

10 which—

Figure 1 is a face view of the lining; and Fig. 2 is a sectional view on the line 2 2, Fig. 1.

The lining is in the form of a flat disk A,

15 with central opening a and a flaring edge B, whose inner face has a series of radial corrugations b.

I claim—

19 The design for a switch-cap lining herein shown and described.

20 In testimony whereof I have signed my name to this specification in the presence of two subscribing witnesses.

GEORGE B. THOMAS.
